UNITED STATES PATENT OFFICE.

JOHN D. McCORD, OF MANILA, PHILIPPINE ISLANDS.

COPRA-DRYING APPARATUS.

1,219,016.

Specification of Letters Patent. Patented Mar. 13, 1917.

Application filed March 20, 1916. Serial No. 85,390.

To all whom it may concern:

Be it known that I, JOHN D. McCORD, a citizen of the United States of America, and resident of the city of Manila, Philippine Islands, have invented certain new and useful Improvements in Copra-Drying Apparatus, of which the following is a full, clear, and exact description.

My invention relates to the manufacture 10 of copra and more particularly to apparatus for drying the shelled meats of cocoanuts preparatory to the completion of the process of converting the same into copra.

The primary objects of my invention are 15 to construct a drying apparatus wherein provision is made for a plurality of trays or galleries upon which the cocoanut meats are deposited and having its heat flues so disposed that the ovens or chambers into 20 which the trays are placed will be evenly heated throughout their entire area. It is likewise an object of my invention to construct the apparatus in a unit or sectional form so that additional ovens or tray compartments may be added at a comparatively 25 small expense. Another object is the provision of a drying apparatus of this type that is duplex in character—that is, the ovens or tray compartments are distributed 30 upon opposite sides of a central heating plant or blower. Further objects of my invention are to provide a drying apparatus that is simple and easy to operate, comparatively inexpensive to manufacture, and is 35 effective in carrying out the objects for which the same is designed. Other objects of my invention will be obvious to mechanics and others skilled in the art to which the same pertains after an understanding 40 is had of the construction thereof as described in the annexed specification.

I prefer to accomplish the divers objects 45 of my invention by the means and in the manner hereinafter fully described and as more particularly pointed out in the appended claims, reference being had to the accompanying drawings forming a part of this specification.

In the drawings—

50 Figure 1 is a vertical front elevation of one of my improved drying apparatuses showing the same constructed of six duplex drying units or tray compartments disposed three upon either side of a central heating plant and blowers;

55 Fig. 2 is a horizontal sectional view taken

on line 2—2, Fig. 1, showing two double units or compartments with the trays removed and drawn to an enlarged scale;

Fig. 3 is a vertical section taken on line 63 3—3, Fig. 2, showing a fragmentary portion of the lower left-hand corner of the end unit or compartment;

Fig. 4 is a fragmentary detail view of a portion of the heating plant and the adjacent unit or compartment, the latter being shown in vertical section and portions of the walls of the former being broken away to disclose the construction of portions of the interior thereof; 70

Fig. 5 is a horizontal section taken on line 5—5, Fig. 1, showing a plan of the lower air flues of one of the batteries of compartments, the arrows indicating the course of the heated air upon leaving the 75 furnace;

Fig. 6 is a vertical section on line 6—6 of Fig. 1, showing the baffle plates in the vertical end flue of the smoke conduit, the arrows indicating the course of the heated 80 products of combustion;

Fig. 7 is a transverse vertical section on line 7—7 of Fig. 1, the trays having been removed; and

Fig. 8 is an enlarged detail of a sliding 85 shutter which may be applied to all openings leading into or from the respective compartments.

Referring to the drawings, wherein it 90 will be observed similar reference characters have been employed to designate the same parts in the divers figures, A is a suitable foundation or base of masonry or the like that is substantially rectangular in shape and is adapted to support a plurality of compartments upon either side of a centrally 95 disposed heater B. The heater preferably is disposed below the horizontal plane of the bottom of the compartments and comprises a fire box or combustion chamber 10 disposed above suitable grate bars 11, and has an ash pit 12 below the latter from which the ash is removable through a horizontally elongated doorway 13. The heater is preferably provided with double-walls 14 as 100 shown in detail in Fig. 4 of the drawings, that are spaced away from each other by spools or fillers 15 in order to provide an air flue or jacket 16 entirely surrounding the heater excepting where suitable outlets or 105 openings are made as hereinafter more fully appears. In order to protect the inner top 110

wall I prefer to bolt or otherwise secure to the under surface thereof one or more metal plates 17 of greater thickness than the metal from which the walls are made.

- 5 The top member of the flue 16 surrounding the heater is preferably provided with a centrally disposed opening 18, to the edge whereof is secured the lower end portion of a pipe 19 that has its upper portion 20 flared 10 or funnel-shaped and is connected with the outlet of a suitable blower 21. This blower may be of any type or size consistent with the quantity of draft or circulation desired in the air flue or jacket 16, and is mounted 15 upon horizontal brackets 22 projecting from suitable wall-plates 23 secured to the vertical exterior walls of the adjacent drying compartments.

The heated products of combustion pass 20 from the combustion chamber of the heater through an outlet flue 24 that extends the entire width and length of the drying compartments upon either side of the heater, and its admission to this flue 24 is regulated 25 by means of a suitable pivoted damper 25 extending across its ends adjacent the combustion chamber. Owing to the fact that the construction and arrangement of the units are the same upon either side thereof, 30 it is only necessary to describe one unit. Said unit or drying compartment preferably comprises a rectangular-shaped metal box consisting of vertical side walls 26, a rear wall 27, and a horizontal top wall 28, that 35 are formed of sheet metal, the front portion or wall being left open so that access may be readily had to the interior. This open front is closed by a suitable hinged door or front plate 29 that is adapted to be locked 40 in closed position by latch bolts 30 of any suitable construction. A plurality of horizontal rows of perforations 31 are made in the side walls 26 and slightly above each row an L-shaped angle metal strip 32 is secured 45 upon the inner surface of these walls so that the trays 33, having perforated bottoms containing the cocoanut meat, may be placed thereon in a compact and convenient manner.

50 Outside the top and side walls of the compartment, and spaced a distance therefrom, are outer walls 34 and 35, respectively, so that an air flue or jacket 36 is provided around the side and top of the compartment.

55 Owing to the fact that I place two compartments back to back as illustrated in Fig. 2 of the drawings, I have found it unnecessary to form an air flue or jacket at the rear of each of said compartments. At convenient points in the bottom plate 37 of the compartments I have provided openings 38 that communicate with an extension air flue 39 of the main air flue 16. The air flue 16 is adapted to communicate with the interior 65 of each compartment through openings 41

made in the bottom wall plate of the latter, so that the air may directly enter and circulate in the interior thereof. The combustion flue 24 is co-extensive with the air flues and is disposed exteriorly thereto to the 70 outer side wall of the end unit, where it is disposed vertically as shown at 42 in Fig. 3 of the drawings and is divided by suitable baffles 46 so as to permit the heated products of combustion to be directed down at the 75 sides of said flue and up through the central portion to the chimney or stack 44, as shown in Fig. 6 of the drawings.

In order to conduct the heated air to the respective chambers, and distribute the same 80 evenly, thus causing it to travel a greater distance or until its efficiency is spent, I have provided baffles or channel plates 45 in the lower air flue 16 that are adapted to conduct the heated air back and forth under the 85 respective units, and control the same by a damper 40.

From the above it will be observed that the air pumped from the blower 21 is forced down and caused to circulate through the 90 compartment 16, around the baffles 45, where it becomes highly heated and then passes into the vertical flues 39 alongside each drying compartment and enters said compartments through the openings 31. 95 This air also passes directly through the openings 41 in the bottom of each compartment, where it circulates around the perforated drying trays 33 containing the cocoanut meats, and thoroughly dries the latter, 100 passing out through an outlet 50 in the top wall of each compartment, which outlet is controlled by a damper 51. This heated air under ordinary conditions would cool after traveling a short distance, but owing to the 105 fact that the flues for conducting and distributing the air are surrounded or covered upon their outside by the heater flues the temperature of this air does not materially decrease but is maintained hot throughout 110 its circulation. It will likewise be observed that the combustion flues do not in any way communicate with either the dry air flues or the drying chambers, but are insulated therefrom, thus permitting the cocoanut 115 meats to be treated and dried with clean heated air that has little or no deleterious effect upon it.

While I have herein illustrated and described certain specific means for carrying out my invention and its objects, it, of course, will be obvious to others skilled in the art to which it appertains that divers modifications or refinements thereof are possible without materially departing from the 120 spirit of my invention. I therefore desire it understood that all such changes in the structure are contemplated as included within the scope of my invention as expressed in the appended claims. 130

What I claim as new is:

1. A drying apparatus comprising a double walled drying chamber, a heat flue surrounding said chamber, and means for circulating air between the double walls of said chamber and into same.
2. A drying apparatus comprising a drying chamber, an air flue surrounding said chamber and communicating therewith, a heat flue surrounding said air flue, and means for forcing air into said first-mentioned flue and into said chamber.
3. A drying apparatus comprising a drying chamber, a heater, a flue leading from said heater around said chamber, and means for circulating air between said flue and chamber and into the latter.
4. A drying apparatus comprising a drying chamber, a heater, a flue leading from said heater around said chamber, an air flue interposed between said heater flue and chamber and communicating with the latter, and means for forcing heated air into said air flue.
5. A drying apparatus comprising a drying chamber provided with an exterior air space, a heater having an air space exterior thereto, means establishing communication between said chamber air space and said heater air space, and a flue leading from said heater and surrounding said drying chamber and its respective air space.
6. A drying apparatus comprising a drying chamber, a blower, an air flue surrounding said chamber and transmitting air from said blower to said chamber, a heater disposed in an intermediate portion of said air flue, and a heat flue leading from said heater around said chamber outside said air flue.
7. A drying apparatus comprising a plurality of drying chambers, heat flues surrounding said chambers, and air flues surrounding said chambers and interposed between the same and said heat flues.
8. A drying apparatus comprising a plurality of drying chambers, air flues surrounding said chambers and communicating therewith, a heater, and heat flues lead-
9. A drying apparatus comprising a plurality of drying chambers arranged in pairs and spaced from each other side by side, air flues surrounding said chambers and disposed between each pair thereof and communicating therewith, a heater, and heat flues disposed exteriorly of said air flues and surrounding each group of chambers.
10. A drying apparatus comprising a heater, drying chambers arranged in pairs and grouped upon each side of said heater, an air jacket surrounding said heater, flues leading from said jacket and surrounding and communicating with each pair of chambers, a blower communicating with said jacket, and heat flues leading from said heater and surrounding each group of chambers outside said air flues.
11. A drying apparatus comprising a drying chamber, heat flues surrounding said chamber, and air flues surrounding said chamber and disposed between the same and said heat flues, one leg of said air flue provided with baffles to provide a longer circulation of the air therein.
12. A drying apparatus comprising a plurality of drying chambers, heat flues surrounding said chambers, and air flues surrounding said chambers and interposed between the same and said heat flues, said air flues provided with longitudinal baffles in its lower member around which the air is adapted to circulate.
13. A drying apparatus comprising a plurality of drying chambers, heat flues surrounding said chambers the top member whereof is provided with longitudinal baffles permitting of a double circulation of the heated products of combustion through said member, and air flues interposed between said chambers and heat flues one member whereof is provided with baffles whereby the air circulates back and forth therein.

Signed at the city of Manila, Philippine Islands, this 11th day of February, 1916.

JOHN D. McCORD.
